CIRCUIT INTERRUPTER

Albert P. Strom, Forest Hills, Pa., assignor to
 Westinghouse Electric & Manufacturing Company, East Pittsburgh, Pa., a corporation of Pennsylvania

Application September 8, 1938, Serial No. 228,931

27 Claims. (Cl. 200—150)

This invention relates to circuit interrupters, and more particularly to high voltage, high power circuit breakers of the liquid immersed type.

Modern circuit breakers which are capable of interrupting a large number of volts per inch of contact separation employ various means for controlling the arc after it is drawn. The first factors which are sought to be controlled are the location, elongation, restriction and relative motion of the arc with respect to the arc extinguishing liquid and the pressure within the arcing chamber.

A number of schemes have in the past been employed to obtain the requisite arc control as, for example, those which utilize the magnetic properties of the current in the circuit, those which utilize the thermal properties of the arc itself, those which use mechanical means independent of the circuit conditions or combinations of any two or all of the schemes mentioned.

The main object of my invention is the provision of a high power circuit breaker having improved interrupting ability and wherein arc control is accomplished substantially by mechanical means.

A further object of my invention is the provision of a circuit interrupter employing arc extinguishing means wherein the arc to be extinguished is rapidly lengthened and subjected to a strong deionizing action along the entire length of the arc.

Another object of the invention is the provision of arc extinguishing means for high voltage, high power circuit interrupters wherein rapid deionization of the arc is obtained by squeezing the arc into a very narrow slot or passage filled with arc extinguishing liquid.

Another object of my invention is the provision of a high voltage circuit breaker having arc extinguishing means equally effective over a wide range of current values.

A still further object of my invention is the provision of a circuit breaker of the above named type employing a relatively small number of moving parts of light weight which may be accelerated rapidly to obtain high speed operation of the breaker without the expenditure of a large amount of power.

Other objects and advantages relate to the arrangement of the various parts of the breaker structure and will appear more fully in the following description when taken in connection with the accompanying drawings, in which:

Figure 1 is a side assembly view partially in

elevation and partially in section showing the circuit interrupter of my invention.

Fig. 2 is a sectional view of the arc extinguishing structure of the interrupter in Fig. 1, showing the interrupter in the closed circuit position.

Fig. 3 is a sectional view similar to that of Fig. 2, showing the interrupter in the open circuit position.

Fig. 4 is a fragmentary sectional view of the arc extinguishing device of my circuit interrupter taken along the line IV—IV of Fig. 2.

Fig. 5 is a cross sectional view of the arc extinguishing device of my circuit interrupter taken along the line V—V of Fig. 2.

Fig. 6 is a fragmentary sectional view showing a modified form of arc extinguishing device which may be used in the interrupter housing shown in Fig. 1.

Fig. 7 is a cross sectional view of a modified form of an extinguishing device similar to that shown in Fig. 6, taken along the line VII—VII of Figure 9.

Fig. 8 is another sectional view of the interrupter shown in Fig. 6 taken longitudinally along the line VIII—VIII thereof.

Fig. 9 is a vertical sectional view of an arc extinguishing device showing a somewhat different arc control arrangement than that shown in Fig. 6.

Fig. 10 is a sectional view of another form of arc extinguishing device constructed in accordance with the principles of my invention.

Fig. 11 is a cross sectional view of the arc extinguishing device of Fig. 10 taken along the line XI—XI.

Fig. 12 is another cross sectional view of the arc extinguishing device of Fig. 10 taken along the line XII—XII.

Fig. 13 is an assembly view partially in elevation and partially in section showing a further form of circuit interrupter embodying my invention.

Fig. 18 is a view of the arc extinguishing de-

vice of Fig. 17 with certain of the operating levers removed to more clearly show the contact arrangement, and

Fig. 19 is a cross sectional view of the arc extinguishing device of Fig. 15 taken along the line XIX-XIX thereof.

In Figure 1, the reference numeral 21 designates a base having an upper supporting plate 23 to which is secured a cylindrical support and strain member 25 of insulating material. To the upper end of the cylindrical member 25 is secured an annular support plate 27 which in this instance serves to support the arc extinguishing structure of the circuit interrupter and also serves to support the external housing of the interrupter as will appear more fully hereinafter. Also mounted upon the support plate 23 is a flanged support member 29 which, in turn, carries a tubular weather-proof housing 31 preferably of porcelain or other suitable material. Between the housing 31 and the annular support plate 27 is disposed an annular expansion member 33 of C-shaped cross section for the purpose of maintaining the weather-proof housing 31 in compression. It will be understood that suitable sealing means as gaskets are employed between the tubular strain member 25 and the base 21 as well as between the outer housing 31 and the support flange 29 and the base 21 so as to prevent the escape of arc extinguishing liquid with which the housing structure is filled.

Suspended from the annular support plate 27 and projecting downwardly into the tubular strain member 25 is an arc extinguishing device generally indicated at 35 in Fig. 1 and more clearly shown in Figs. 2 to 5, inclusive. The arc extinguishing structure 35 comprises a cylindrical housing 37 of insulating material, the upper end of which is provided with a metallic framework 39 by which the arc extinguishing device is supported from the annular plate 27.

A pair of contact supports 41 are positioned in diametrically opposed relation within the tubular housing 37 and may be secured to the housing by means of bolts 43, as shown. The contact supports 41 each has an outwardly projecting portion at the lower end thereof which extends through the side walls of the housing 37 to form external terminals 45 and 47, respectively. The contact supports 41 also have an upwardly projecting arm 49 to which is pivoted a contact actuating arm 51.

Each of the contact carrying arms 51 has a movable contact 53 secured to the lower end thereof. The two contacts 53 are adapted for cooperative engagement with each other and are maintained in spring pressed engagement by means of springs 55. Flexible shunts 57 provide a low resistance circuit from the respective contacts 53 to the terminal members.

Disposed immediately below the contacts 53 is a slot-like arc passage 59 of rectangular cross section and preferably having its opposed inner walls formed of corrugations, as shown in Fig. 2. The arc passage 59 may be formed by the use of a series of circular plates 61 and 63 of insulating material, alternately disposed to provide a stack and having a rectangular slot therein. The slot in the plate 61 is preferably narrower than the slot in the plate 63 so as to provide the corrugated inner surface previously mentioned. The corrugated arc passage wall is favored since it maintains a more liberal quantity of arc extinguishing liquid adjacent the arc path during

arc extinction than is maintained by an arc passage wall having a smooth surface.

The plates 61 and 63 are maintained in compression between the contact supports 41 and a piston chamber member 65 disposed at the lower end of the tubular housing 37. The member 65, the purpose of which will be more fully described hereinafter, may be held in place by an annular plate 67 bolted to a metallic flange 69 secured to the lower end of the casing 31, as shown.

Disposed within the casing 31 and adapted for longitudinal axial movement therein is a contact actuating and barrier member 71 which preferably is constructed of insulating material having a high dielectric strength and heat resistant properties when subjected to the direct action of an arc. The barrier member 71 is substantially the same width as the arc passage 59 and of thickness such that it provides preferably from $\frac{1}{8}$ " to $\frac{1}{8}$ " clearance on the longer sides thereof.

The barrier member 71 is also provided with a rectangular aperture 73 into which the moving contacts 53 project from opposite sides thereof to complete the electrical circuit through the interrupter. The upper end of the barrier member 71 is provided on each side thereof with cam surfaces 75 adapted to engage a roller 77 journaled within the contact actuating arms 51. The cam surfaces 75 and the rollers 77 are also preferably constructed of high dielectric strength insulating material so as to increase the open circuit resistance of the interrupter. The extreme upper end of the barrier member 71 is provided with a coupling member 79 adapted to be connected to a spring actuating mechanism generally indicated at 81 and housed within the chamber 83 as shown in Fig. 1. The lower end of the barrier member 71 extends through a snug fitting aperture in the piston chamber member 65 and is provided with a suitable coupling 85 to which the breaker actuating mechanism, a part of which is shown at 87, is connected.

From the foregoing description, it will be apparent that the actuating mechanism 87 when held in the position shown in Fig. 1, maintains an upward thrust upon the barrier member 71 which, in turn, holds the spring actuating mechanism 81 in compression ready to drive the barrier member 71 downwardly when the operating mechanism 87 is tripped or released so as to effect a circuit opening operation. The electrical circuit through the interrupter as more clearly shown in Figs. 1 and 2 proceeds from a line terminal 89 projecting through the side wall of a cover 91 of the interrupter housing and continues by way of a flexible connection 93 to the support plate 27 which, in turn, is connected to a conductor 95 making connection with the terminal 45 of the contact support 41. The connection then proceeds through the flexible shunt 57 to the left-hand movable contact member 53 and then to the right-hand contact 53, flexible shunt 57 and the fixed terminal 47. A conductor 97 connects the terminal 47 of the arc extinguishing device 35 to an external terminal 99 extending through the base 21.

In the event that the circuit breaker, as shown in Fig. 1, is connected in a power circuit through the external terminals 89 and 99 and it is desired to interrupt the circuit, the operation of the breaker is as follows:

Upon tripping of the circuit interrupter which releases the operating mechanism 87, the spring means 81 forces the barrier member 71 down-

wardly. The cam surfaces 75 on either side of the barrier member 71 engage the two rollers 77 carried by the contact actuating arms 51 so as to separate these arms and consequently separate the contacts 53. The leading edges of the cam surfaces 75 are so proportioned in connection with the contact actuating arms 51 that the contacts 53 will have separated sufficiently by the time the upper edge of the aperture 73 in the barrier member 71 reaches the former contact position to permit the barrier 71 to pass between the contacts. Thus the arc is established between the contacts 53 and through the aperture 73.

Upon continued movement of the barrier 71, the wedge-shaped upper edge of the aperture 73 is driven into the arc and moves the same downwardly into the slot-like arc passage 59, causing the arc to be lengthened rapidly and to be forced into the confined space on either side of the barrier member. The relative position of the barrier member and contacts with respect to the arc passage upon reaching full open circuit position is shown in Fig. 3.

Inasmuch as the barrier member 71 immediately below the aperture 73 has a reduced width as shown in Fig. 4 so as to form shoulders 101, arc extinguishing liquid is driven by virtue of these shoulders which serve as pistons, upwardly along the arc stream. Also, formation of the arc within the confined slot-like arc passage produces considerable gas as a result of decomposition of the arc extinguishing liquid which, in escaping from the arc chamber 59, must flow longitudinally of the arc stream on either side of the barrier member 71 towards the upper and open end of the arc chamber. Thus substantially the entire length of the arc is subjected to a violent deionizing action which takes place substantially immediately upon formation of the arc thereby hastening arc extinction. Arc extinction is also facilitated due to the fact that the arc is continuously lengthened during the deionizing process. Although the arc passage on either side of the barrier member 71 is extremely narrow, arcs of large as well as small current magnitude are successfully extinguished since the arc core may spread out laterally in accordance with the current magnitude.

In order to rid the arc passage 59 of undesirable products of decomposition of the arc, I have provided a flushing arrangement adjoining the lower end of the chamber. The flushing arrangement in this instance comprises a piston 103 surrounding the barrier member 71 and operative within the piston chamber 65. The piston 103 is normally held by a spring 105 in the position shown in Fig. 2, that is in engagement with the upper wall of the chamber 65. The chamber 65 is provided with a plurality of passages 107 communicating with the lower end of the arc chamber 59. Thus during the circuit opening operation when the arc pressure within the chamber 59 exceeds a predetermined value, liquid in the lower portion of the chamber will be forced through the openings 107 into the chamber 65 and drive the piston 103 to the position shown in Fig. 3 against the bias of the spring 105. Upon extinction of the arc and subsidence of the pressure within the chamber 59, the spring 105 again returns the piston 103 to its uppermost position driving the oil previously collected above the piston through the passages 107 into the arc chamber 59 and upwardly through the open end thereof so as to flush out any sediment or other im-

purities which may have collected as a result of the circuit interrupting operation.

In the interrupter shown in Figs. 6 and 8, a barrier member 109 is illustrated of somewhat different form than the barrier member 71 previously described. In the modified form the aperture 73 has been omitted and a contact bridging member 111 has been substituted therefor. The bridging contact member 111, when the barrier member 109 is in the closed circuit position, is interposed in contacting engagement between a pair of contacts 113, each of which is secured to the end of a contact support rod 115. The contact support rods 115 are carried within the tubular support guides 117 of the fixed contact terminals 119 secured on diametrically opposed sides of the tubular casing 37.

The contacts 113 are yieldingly maintained in engagement with the bridging contact member 111 by springs 121 surrounding the contact carrying rods 115. The arc extinguisher arrangement shown in Figs. 6 to 9 also differs somewhat from that previously described, in that the shape of the slot-like arc passage has been modified. In this instance the arc passage dimension has been decreased in the direction parallel to the width of the barrier member 109 to substantially the width of the bridging contact member 111, as shown at 123 in Fig. 7. The arc passage 123 is defined by a plurality of alternate plates 125 and 127 of insulating material having slots therethrough the major portion of which have an outline conforming to the cross section of the barrier member 109 with the exception that the portion adjacent the bridging contact member 111 has been enlarged, the enlargement in the plates 127 being greater than in the plates 125 so as to provide an irregular surface.

Thus, when the barrier member 109 is moved downwardly carrying with it the bridging contact member 111 so as to move the bridging member out of contact engagement with the contacts 113, two arcs are drawn one on each side of the barrier member 109 into the arc passage 123. In this arrangement, the two separate arcs are confined respectively to a relatively long and narrow passage and are not permitted to spread laterally to the extent permitted in connection with the structure previously described.

The clearance between the moving barrier member 109 and the edge of the slot forming the arc passage 123 may vary from $\frac{1}{8}$ to $\frac{1}{2}$ inch. Movement of the contact bridging member 111 downwardly into the arc passage 123 also provides a longitudinal flow of arc extinguishing liquid upwardly which assists in extinguishing the arc. The provision of the bridging contact member 111 may under certain conditions be more effective than the arrangement shown in Fig. 2, in that it controls the lengthening of the arc. In the device of Fig. 6, the two arcs are caused to elongate at a rate dependent upon the rate of travel of the barrier member 109, whereas in the arrangement shown in Fig. 2, the arc drawn between the two separating contact members has a tendency to lengthen, due to magnetic action of the current flowing in opposite sides of the loop, and to advance more rapidly than the upper edge of the aperture 73 within the barrier member 71, thereby producing somewhat higher pressures under certain conditions, within the arc passage tending to retard movement of the barrier member.

Fig. 9 shows an arc extinguishing device substantially of the same form as shown in Figs. 6

and 8 with the exception that an aperture 129 is provided in the barrier member 109 immediately above the bridging contact 111. The provision of the aperture 129 provides a more turbulent flow of arc extinguishing liquid adjacent the bridging contact member 111 and for this reason may under certain current conditions be more effective in bringing about arc extinction. In other respects the operation of the interrupter shown in Fig. 9 is substantially the same as that shown in Figs. 6 and 8.

The arc extinguishing device illustrated in Figs. 10 through 12 differs from the arrangement shown in Fig. 2 primarily in that it is specifically designed to bring about effective arc extinction over a very broad range of current values. As shown in Fig. 10, a barrier member 131 is provided, the lower end of which is of wedge shape and is adapted to force the arc formed between the separating contacts 133 into a wedge-shaped arc passage 135. A cam actuating mechanism for contact operation, as shown in Fig. 2, is here employed.

The V-shaped arc passage 135 is preferably formed of plates of insulating material 137, the slots therein being of rectangular cross section and varying in width from the uppermost plate to the lowermost plate so as to cause the passage to converge towards the lower end thereof. The inclined side walls of the passage 135 are also corrugated by providing the plates 137 with slots of slightly different widths. The moving barrier member 131 may be actuated to the open and closed position by means of suitable mechanism connected to the operating rod 139 coupled to the side edges of the barrier member 131 by brackets 141.

From the foregoing description it is apparent upon separation of the contacts 133 while the interrupter is carrying extremely high currents, the wedge shape portion of the barrier member 131 will not confine the arc to an appreciable extent during the initial part of the circuit interrupting operation. This permits ready escape of the products of decomposition of the arc which flow longitudinally along the arc stream, as it is lengthened by the barrier member 131, so as to extinguish the arc without causing the arc energy to be materially increased.

In the event that an arc is being interrupted of very small current magnitude, very little interrupting effect will be produced until the wedge shape portion of the barrier member 131 has moved the arc a considerable distance into the wedge shape passage 135. However, as the barrier member 131 approaches the lower limit of its stroke, the effective width of the arc passage on either side of the barrier member becomes very small, thus subjecting the low current arc to substantially the same deionizing action as is produced with currents of larger magnitude but where the arc passage is of a greater width.

It will be observed that the modifications shown and described in Figs. 6 through 12, inclusive, are also adapted for operation in a weather-proof housing of the low oil capacity type, as shown in Fig. 1. The respective barrier members in each of the modifications are also adapted to be actuated to their open circuit positions by means of spring actuated accelerating means, as shown at 81 in Fig. 1.

In Figs. 13 through 19, a circuit interrupter is shown having a contact arrangement adapted for operation with a barrier member and arc extinguishing passage of the tubular form. In Fig. 75

13 the external housing of the interrupter is substantially the same as that shown in Fig. 1 and need not be further described. The housing, as shown in Fig. 13, encloses an interrupting unit 145 which is more fully shown in Figs. 14 to 19. The arc extinguishing structure 145 comprises a cylindrical casing member 147, the upper portion of which is provided with a support flange 149 across which is secured a conducting support 151. Centrally disposed of the support 151 and projecting axially within the casing 147 is a fixed contact rod 153.

On diametrically opposed sides of the casing 147 are cutout portions 155 to provide suitable openings for the reception of an operating mechanism which will be more fully described herein-after.

Within the casing 147 adjacent the lower edge of the cutout portions 155, is a flanged tubular metallic support 157 for carrying a movable contact assembly generally indicated at 159. The tubular support 157 carries a plurality of contact supporting brackets 165, each of which pivotally supports a moving contact 167 at the lower end thereof. The contacts 167 are encircled by a plurality of springs 169 so as to yieldingly maintain the contacts in engagement with the lower end of the fixed contact rod 153. Disposed below the tubular support 157 are a plurality of plates 171 of insulating material, all of which have a circular aperture therethrough with alternate plates having apertures of a different diameter so as to produce an arc passage 173 having corrugated side walls. Joined to the lower end of the fixed contact rod 153 is a filling member 175 of insulating material having a diameter substantially equal to the diameter of the lower end of the contact rod. The filling member 175 extends to the bottom of the arc passage 173 and is adapted to register with a suitable opening in a plate 177 forming the bottom of the arc extinguishing passage. Thus the side edges of the plates 171 and the filling member 175 produce an arc extinguishing chamber 45 of tubular cross section.

Surrounding the fixed contact rod 153 is a tubular barrier member 179 of insulating material which is adapted to be moved downwardly into the tubular arc passage 173 so as to move 50 an arc established between the contacts 167 and the contact rod 153 into the arc passage. Movement of the barrier member 179 is accomplished by an operating mechanism supported upon an external flange 161 encircling the casing 147.

55 The operating mechanism includes a collar 181 secured about the tubular barrier member 179 and to which one end of a pair of actuating links 183 is pivoted. The other end of the links 183 is pivoted by means of a shaft 185 to a pair 60 of sliding block or bearing members 187. The bearing members 187 are adapted to slide in elongated slots 189 provided in a pair of spaced upright brackets 191 which are secured to a support plate 163 mounted on the flange 161. The link members 183 are connected by a shaft 193 to one end of a pair of link members 195 65 fixedly joined together by a sleeve 197 and through which a shaft 199 is adapted to pass so as to pivotally support the link members 195 to two upstanding brackets 201 secured to a second support plate 164 also mounted on the flange 161. The other end of the link members 195 are joined by a shaft 203 to which an operating rod 205 of a suitable operating mechanism may be connected. As shown in Fig. 13,

the rod 205 extends downwardly between the arc extinguishing device 145 and the interrupter housing and connects to a bell crank 207 which is operatively coupled to a mechanism not shown, for actuating the interrupter to open and closed circuit positions.

The foregoing linkage including the members 183 and the link members 195, are disposed with respect to their pivotal connections such that upon rocking the links 195 about the shaft 199 in a counter-clockwise direction as viewed in Fig. 14, a substantially straight line motion in the downward direction, will be imparted to the tubular barrier member 179.

In order to prevent the lower end of the tubular barrier member 179 from striking the contacts 167 means are provided for rocking these contacts about their pivotal supports out of engagement with the contact rod 153, thereby establishing an arc between at least one of the contact fingers 167 and the fixed contact rod 153 and providing sufficient clearance to permit the barrier member 179 to be moved downwardly into engagement with the arc and force the same into the tubular arc passage 173.

In order to rock the contact fingers 167 out of engagement with the fixed contact rod 153, the contact fingers are provided with outwardly extending projections 209 adjacent their pivoted ends. Immediately below the projections 209 is disposed an annular member 211 having two upstanding arms 213 fixedly secured thereto and disposed at diametrically opposed points thereon. Pivoted to the upper end of each arm 213 is a bifurcated arm 215, the legs of which are preferably integrally joined together by a sleeve 217, which sleeve provides for the passage of a shaft 219 which, in turn, is journaled in the two upper support brackets 201.

The sleeve 217 has an upstanding arm 221, the end of which is provided with a roller 223. The roller 223 is adapted to engage a cam surface 225 disposed upon the sleeve 197 joining the link members 195. With particular reference to Figs. 14 and 15, it will be noted that as the link members 195 are rotated counter-clockwise about the shaft 199, the cam surface 225 engaging the roller 223 will cause the arm 221 rigidly secured with respect to the arms 215, to be rocked in a clockwise direction about the shaft 219. This clockwise rotation of the arms 215 will raise the arms 213 and the annular member 211 which is brought into engagement with the projections 209 so as to rock the contacts 167 out of engagement with the contact rod 153 and thereby permit the tubular barrier member 179 to proceed downwardly unobstructed into the tubular arc passage 173.

The circuit through the arc extinguishing device 145 proceeds from the contact member 151 through the fixed contact rod 153, the contact fingers 167 through the flexible shunts provided between these contact fingers and the contact support 165 and from the support 165 to the support plate 164 by a shunt connection 210. When the unit 145 is disposed in the housing, as shown in Fig. 13, the terminal support member 151 may be connected to an external terminal 222 by a flexible connector 224. The support plate 164 may be connected by a conductor 226 to an external terminal 227 extending through the base of the interrupter housing.

The arc extinguishing operation of the arc extinguishing device 145 is similar to that previously described. From the foregoing description

of the mechanics of the moving parts constituting the contact and barrier member operating means, it is apparent that as the barrier member 179 is moved downwardly and the contacts 167 are withdrawn from the fixed contact 153, an arc is drawn between the separating contact surfaces. This arc is caused to be rapidly elongated by the downwardly movement of the barrier member 179 and consequently is driven into the tubular arc passage 173 and forced to play between the fixed contact member 153 and at least one of the contact fingers 167 while being looped over the lower end of the barrier member 179. From $\frac{1}{16}$ to $\frac{1}{8}$ " clearance is preferably provided between the barrier member 179 and the side walls of the arc passage 173. It is thus seen that as the barrier member 179 is moved into the arc chamber 173, the elongated arc is confined to a high degree and subjected to the intense blast of the products of decomposition of the arc which in escaping from the passage must flow in the direction opposite to that of movement of the barrier member. The barrier member also produces a flow of arc extinguishing liquid which it displaces upwardly due to its downward movement into the passage. Thus an arc drawn by the contacts arranged in this manner in conjunction with the tubular barrier member is subjected to an intense deionizing action and effectively extinguished.

The tubular form of arc passage is particularly effective in extinguishing arcs covering a wide range of current values in that the arc core, for a given current value, can spread out circumferentially of the passage in accordance with the current magnitude.

The lower end of the arc passage 173 is in this instance as in the previous modifications illustrated, also provided with spring actuated flush means constructed and arranged in the manner previously described in connection with the arc extinguishing device shown in Fig. 2.

Although I have shown and described a specific circuit interrupting structure and various arrangements of arc extinguishing devices therefore, it is to be understood that the same is for the purpose of illustration and that changes and modifications may be made by those skilled in the art without departing from the spirit and scope of the appended claims.

I claim as my invention:

1. In a circuit interrupter of the liquid immersed type, a quantity of arc extinguishing liquid, an arc extinguishing structure immersed in said liquid, said arc extinguishing structure comprising means of insulating material defining an arc chamber open at one end and closed at the other, means for establishing an arc outside of but adjacent the open end of said arc chamber, means for moving the arc into said arc chamber, and resilient means disposed at the closed end of said arc chamber movable in response to pressure created by the arc within said arc chamber to a predetermined position, said resilient means being returnable to its normal position upon subsidence of the pressure within said arc chamber to force arc extinguishing liquid entrapped in the closed end of said arc chamber from the arc chamber through the open end thereof.

2. In a circuit interrupter of the liquid immersed type, a quantity of arc extinguishing liquid, an arc extinguishing structure immersed in said liquid, said arc extinguishing structure comprising means of insulating material defining an arc chamber open at one end and closed at

the other, means for establishing an arc outside of but adjacent the open end of said arc chamber, means for moving the arc into said arc chamber, means at the closed end of said arc chamber for moving a quantity of arc extinguishing liquid through said arc chamber following arc extinction, and resilient energy storing means for actuating said liquid moving means, said energy storing means being stressed to store energy therein in response to arc pressure within said arc chamber.

3. In a circuit interrupter of the liquid immersed type, a quantity of arc extinguishing liquid, an arc extinguishing structure immersed in said liquid, said arc extinguishing structure comprising means of insulating material defining an arc chamber open at one end and closed at the other, means for establishing an arc outside of but adjacent the open end of said arc chamber, means for moving the arc into said arc chamber, a piston chamber communicating with the closed end of said arc chamber having a piston movable therein, and means biasing said piston toward one end of said piston chamber, said piston being moved in response to pressure within the arc chamber in a direction to stress said biasing means, said biasing means returning said piston to its normal position in response to the subsidence of pressure within the arc chamber to move a quantity of arc extinguishing liquid through the arc chamber.

4. In a circuit interrupter, a quantity of arc extinguishing liquid, means of insulating material defining a narrow arc chamber of generally rectangular cross section open at one end and closed at the other end immersed in said liquid, a blade member at least partially of insulating material having a portion normally outside said arc chamber and movable into the arc chamber during circuit interruption and a portion normally within said arc chamber movable through the closed end thereof during circuit interruption, a pair of contacts disposed adjacent the open end of said arc chamber and adapted to be moved to open circuit position to draw an arc transversely of said arc passage and in the path of movement of said portion of blade member normally outside said arc chamber, and operating means for sequentially separating said contacts and moving said blade member into engagement with the arc to project the latter into said arc chamber, said portion of the blade member being moved out of said arc chamber displacing less liquid than said portion being moved into the arc chamber to subject the arc to a flow of liquid to assist arc extinction.

5. In a circuit interrupter, a quantity of arc extinguishing liquid, means of insulating material defining a constricted arc passage of considerable length immersed in said liquid, said arc passage being closed at one end and open at the other, a pair of separable contacts at least one of which is permanently positioned outside said arc passage adjacent the open end thereof, a movable member of insulating material supporting the other of said pair of separable contacts, said movable member having a portion normally outside said arc passage and a portion normally inside said passage, and means for moving said member of insulating material to establish an arc within said arc passage and to cause said portion outside said passage to move into said passage and said portion inside said passage to move through the closed end thereof, said portion normally outside said arc passage displacing

more liquid than said portion normally inside said passage to provide a longitudinal flow of arc extinguishing liquid along the arc to aid in extinguishing the arc.

5 6. In a circuit interrupter, a quantity of arc extinguishing liquid, means of insulating material defining an elongated arc passage open at one end but otherwise completely enclosed immersed in said liquid, a plunger member of insulating material movable into said arc passage to provide an arc path of constricted cross section between the plunger member and one wall of said passage, a fixed contact disposed adjacent the open end of said arc passage, a cooperating contact carried by said plunger member and movable therewith into said arc passage to establish an arc along said constricted arc path, and a guide member movable with said plunger and extending from said cooperating contact through the closed end of said arc passage, the products of decomposition of the arc being caused to flow longitudinally of the arc path towards the open end of said arc passage, said guide member having a cross-section less than said plunger member to cause a flow of arc extinguishing liquid longitudinally of the arc to assist the products of decomposition of the arc in extinguishing the arc.

7. In a circuit interrupter, means of insulating material defining a constricted arc passage of considerable length, said arc passage being closed at one end and open at the other, arc extinguishing liquid in said passage, a pair of contacts permanently positioned outside said arc passage adjacent the open end thereof, a barrier member 35 of insulating material disposed between said contacts and extending into said arc passage and through the closed end thereof, said barrier member carrying a bridging contact normally disposed between said pair of contacts to interconnect the same, said bridging contact being movable with said barrier member into said arc passage to establish an arc on each side of said barrier member within the arc passage, the portion of said barrier member being moved out of 45 said passage during the circuit interrupting operation having a cross-section less than the portion of said barrier being moved into said passage to cause a flow of arc extinguishing liquid longitudinally of the arcs toward the open end of said arc passage.

8. In a circuit interrupter, means of insulating material defining an arc chamber having a generally rectangular cross section, said arc chamber being open at one end but otherwise completely closed, two opposing walls of said arc chamber converging in a direction away from the open end thereof, means for establishing an arc across the open end of said arc chamber, and a wedge member of insulating material movable into the arc chamber whereby the arc is progressively lengthened and constricted in cross section as it is forced into said arc chamber by said wedge member.

9. In a circuit interrupter, means of insulating material defining an arc chamber having a generally rectangular cross section, said arc chamber being open at one end but otherwise completely closed, two opposing walls of said arc chamber converging in a direction away from the open end thereof, a pair of separable contacts for establishing an arc across the open end of said arc chamber, a wedge member of insulating material movable between said contacts for initiating arc movement into said arc chamber, and an actuating mechanism for simultaneously operating said

contacts to open circuit position and moving said wedge member into engagement with the arc, said actuating mechanism separating said contacts a distance sufficient to permit said wedge member to be moved therebetween without engaging the contacts.

10. In a circuit interrupter, a quantity of arc extinguishing liquid, a casing immersed in said liquid, means of insulating material disposed in one end of said casing defining a tubular arc passage open at one end, a fixed contact disposed adjacent the open end of said tubular arc passage, a plurality of movable contacts cooperating with said fixed contact to establish the circuit through the interrupter, means for moving said movable contacts out of engagement with said fixed contact to establish at least one arc radially across said tubular arc passage, and a tubular member of insulating material movable in surrounding relation with respect to said fixed contact into said tubular arc passage in response to the separation of said movable contacts from said fixed contact for causing said arc to play in an extended loop within said tubular arc passage.

11. In a circuit interrupter, a quantity of arc extinguishing liquid, a tubular casing immersed in said liquid, an arc extinguishing chamber of circular cross section and open at one end disposed in one end of said casing, a filling member of insulating material disposed axially of said arc chamber to provide an annular arc passage, a contact member coextensive with said filling member having a contact portion adjacent the open end of said arc passage, pivotally mounted contacts adapted to cooperate with said contact portion to establish the circuit through the interrupter, means for rocking said contacts out of engagement with said contact portion to establish at least one arc across said annular arc passage, a tubular barrier member of insulating material normally surrounding said contact member and slideable longitudinally thereof over said filling member into said annular arc passage, and means operative in unison for rocking said contacts and for moving said tubular barrier member into said annular arc passage to cause said arc to be looped over the end of said barrier member and play in said annular arc passage.

12. In a circuit interrupter of the liquid immersed type, a quantity of arc extinguishing liquid, an arc extinguishing structure immersed in said liquid, said arc extinguishing structure comprising means of insulating material defining an arc chamber open at one end and closed at the other, means for establishing an arc outside of but adjacent the open end of said arc chamber, means for moving the arc into said arc chamber, a piston member movable into said arc chamber to establish a flow of arc extinguishing liquid along said arc, a piston member movable into said arc chamber to establish a flow of arc extinguishing liquid along said arc, and means adjacent the closed end of said arc chamber for moving an additional quantity of arc extinguishing liquid through said arc chamber in accordance with predetermined pressure conditions in said arc chamber.

13. In a circuit interrupter of the liquid immersed type, a quantity of arc extinguishing liquid, an arc extinguishing structure immersed in said liquid, said arc extinguishing structure comprising means of insulating material defining an arc chamber, means for establishing an arc in said arc chamber, a plunger at

least partially of insulating material movable into said arc chamber for confining the arc between the plunger and a wall of said arc chamber and for causing a flow of insulating liquid in contact with the arc and means operative in response to predetermined pressure conditions within said arc chamber for producing an additional flow of arc extinguishing liquid through said arc chamber.

10. 14. In a circuit interrupter, a pair of fixed, spaced members of insulating material defining an annular arc chamber therebetween, contacts adjacent one end of said arc chamber, means for establishing an arc between said contacts, and a tubular member at least partially of insulating material movable upon the striking of said arc between said contacts and into said annular arc chamber to substantially fill said chamber and for causing said arc to play in the constricted space between said tubular member and opposite walls of said annular arc chamber.

15. 15. In a circuit interrupter, means of insulating material defining an annular arc chamber, separable contacts for establishing an arc radially across said annular arc chamber and a tubular member at least partially of insulating material movable against said arc into said annular arc chamber to substantially fill said chamber and for directing the arc into said chamber and causing it to play in an extended loop about one end of said tubular member.

30. 16. In a circuit interrupter, means of insulating material defining an annular arc passage open at one end, a fixed contact disposed adjacent the open end of said annular arc passage, a plurality of movable contacts cooperating with said fixed contact to establish the circuit through the interrupter, means for moving said movable contact out of engagement with said fixed contact to establish at least one arc radially across said annular arc passage, and a tubular member of insulating material movable in surrounding relation with respect to said fixed contact into said annular arc passage in response to the separation of said movable contacts from said fixed contact for causing said arc to play in an extended loop within said annular arc passage.

40. 17. In a circuit interrupter, an arc extinguishing chamber of circular cross section and open at one end, a filling member of insulating material disposed axially of said arc chamber to provide an annular arc passage, a contact member coextensive with said filling member having a contact portion adjacent the open end of said arc passage, pivotally mounted contacts adapted to cooperate with said contact portion to establish the circuit through the interrupter, means for rocking said contacts out of engagement with said contact portion to establish at least one arc across said annular arc passage, a tubular barrier member of insulating material normally surrounding said contact member and slideable longitudinally thereof over said filling member into said annular arc passage, and means operative in unison for rocking said contacts and for moving said tubular barrier member into said annular arc passage to cause said arc to be looped over the end of said barrier member and play in said annular arc passage.

50. 18. In a circuit interrupter, a quantity of arc extinguishing liquid, means of insulating material defining a tubular arc passage immersed in said liquid, separable contacts for establishing an arc adjacent one end of said arc passage, a tubular member of insulating material movable

into engagement with said arc and into said tubular arc passage for causing the arc to be extended into said arc passage, said tubular member causing a flow of arc extinguishing liquid axially of said arc passage to aid in extinguishing the arc, and means for causing an additional flow of arc extinguishing liquid axially of said arc passage.

19. In a circuit interrupter, a quantity of arc extinguishing liquid, means of insulating material defining a tubular arc passage immersed in said liquid, said arc passage being open at one end and closed at the other, separable contacts for establishing an arc radially across the open end of said arc passage, a tubular barrier member of insulating material movable into said tubular arc passage for causing the arc to play in an extended loop about the end of said barrier member within said arc passage, said barrier member causing a flow of arc extinguishing liquid longitudinally of the arc towards the open end of said arc passage and means operative in response to predetermined pressure conditions within said arc passage to cause an additional flow of arc extinguishing liquid through said arc passage.

20. In a circuit interrupter, means of insulating material defining a narrow arc chamber open at one end and closed at the other end, separable contacts disposed outside of said arc chamber adjacent the open end thereof, means mounting said contacts for movement in paths outside of said chamber and extending across the open end thereof, means for operating said contacts to open circuit position to establish an arc across the open end of said arc chamber, a member at least partially of insulating material movable upon separation of said contacts into engagement with said arc substantially transversely thereof and into said arc chamber for moving said arc into said chamber and causing it to play in an elongated restricted path on opposite sides of said movable member, and means along said elongated restricted paths which gives off a gas when acted upon by an arc to aid in extinguishing the arc, the said walls of said arc chamber and the closed end thereof causing said arc extinguishing gas to flow longitudinally of the arc and across the space between said separable contacts at the open end of said chamber.

21. In a circuit interrupter, means of insulating material defining a narrow arc chamber open at one end and closed at the other end, separable contacts disposed outside of said arc chamber adjacent the open end thereof, means mounting said contacts for movement in paths outside of said chamber and extending across the open end thereof, means for operating said contacts to open circuit position to establish an arc across the open end of said arc chamber, a member at least partially of insulating material movable upon separation of said contacts into engagement with said arc substantially transversely thereof and into said arc chamber for moving said arc into said chamber and causing it to play in an elongated restricted path on opposite sides of said movable member, and a quantity of arc extinguishing liquid in said chamber, the side walls of said chamber being so arranged with respect to said member that movement of said member into the chamber towards the closed end thereof causes a flow of arc extinguishing liquid and the products of decomposition of the arc longitudinally of the arc and through the

space between said separable contacts at the open end of said chamber.

22. In a circuit interrupter having a pair of terminals, a first relatively stationary contact having a plurality of contact surfaces connected to one of said terminals, a plurality of pivoted contacts connected to the other terminal and resiliently urged into engagement with said contact surfaces, and means including a tubular member of insulating material telescopically movable over said first contact and operable to sequentially move said pivoted contacts away from said contact surfaces and interpose said member of insulating material between said pivoted contacts and said contact surfaces.

23. In a circuit interrupter having a pair of terminals, means of insulating material defining an elongated arc passage open at one end, a first relatively fixed contact having a plurality of contact surfaces disposed adjacent the open end of said passage and connected to one of said terminals, a plurality of pivoted contacts connected to the other terminal and biased into engagement with said contact surfaces, means for moving said pivoted contacts away from said contact surfaces to establish an arc, and a tubular member of insulating material telescopically movable over said first contact and movable in accordance with movement of said pivoted contacts between said pivoted contacts and said contact surfaces into said arc passage to cause said arc to play in an extended loop between said member of insulating material and the walls of said arc passage.

24. In a circuit interrupter, a quantity of arc extinguishing liquid, means of insulating material defining a narrow arc chamber open at one end and closed at the other end immersed in said liquid, a member at least partially of insulating material having a portion normally outside said arc chamber and movable into the arc chamber during circuit interruption and a portion normally within said arc chamber movable through the closed end thereof during circuit interruption, a pair of contacts disposed adjacent the open end of said arc chamber and adapted to be moved to open circuit position to draw an arc adjacent the open end of said passage, means including said member for projecting the arc into said arc chamber, said portion of the member being moved out of said arc chamber displacing less liquid than said portion being moved into the arc chamber to subject the arc to a flow of liquid to assist arc extinction.

25. In a circuit interrupter, means of insulating material defining a narrow arc chamber, said chamber being open at one end and closed at the other, a member at least partially of insulating material having a portion normally outside said arc chamber and movable into said chamber through the open end thereof during a circuit interruption and a portion normally within said chamber movable through the closed end thereof during a circuit interruption, separable contacts normally disposed adjacent the open end of said arc chamber and adapted to separate to draw an arc adjacent the open end of said chamber, means including said member for projecting the arc into said chamber, said portion of said member being moved out of said arc chamber having less displacement in said chamber than said portion being moved into the arc chamber to create a fluid pressure in said chamber in addition to that which may be created

by the arc to subject the arc to a flow of fluid from said chamber out through the open end thereof.

26. In a circuit interrupter, means of insulating material defining an arc chamber, said arc chamber being open at one end but otherwise completely closed, at least two opposing walls of said arc chamber converging in a direction away from the open end thereof, means for establishing an arc adjacent the open end of said arc chamber, and a wedge member of insulating material movable into the arc chamber whereby the arc is progressively lengthened and constricted in cross section as it is forced into said arc chamber by said wedge member.

15

27. In a circuit interrupter, means of insulating material defining an annular arc passage open at one end, spaced contacts adjacent the open end of said passage, a bridging contact co-operating with said spaced contacts to establish the circuit through said interrupter, means for striking an arc between said spaced contacts, and a tubular member of insulating material movable between said spaced contacts and into said annular arc passage in response to the striking of said arc for causing said arc to play in an extended loop within said annular arc passage.

ALBERT P. STROM.
